(57) **CLAIM**

The ornamental design of a light tower for an industrial vehicle, as shown and described.

DESCRIPTION

FIG. 1 is a front view of an embodiment of a light tower for an industrial vehicle illustrating our new design;

FIG. 2 is a back view thereof;

FIG. 3 is a top side view thereof;

FIG. 4 is a bottom side view thereof;

FIG. 5 is a right side view thereof;

FIG. 6 is a left side view thereof;

FIG. 7 is a front, top, right isometric view thereof;

FIG. 8 is a back, top, left isometric view thereof;

FIG. 9 is a front, top, left isometric view thereof;

FIG. 10 is a back, bottom, right isometric view thereof;

FIG. 11 is a front view of another embodiment of a light tower for an industrial vehicle illustrating our new design;

FIG. 12 is a back view thereof;

FIG. 13 is a top side view thereof;

FIG. 14 is a bottom side view thereof;

FIG. 15 is a right side view thereof;

FIG. 16 is a left side view thereof;

FIG. 17 is a front, top, left isometric view thereof; and,

FIG. 18 is a back, bottom, right isometric view thereof.

The broken lines in the drawings represent portions of the light tower for an industrial vehicle that form no part of the claimed design and are considered necessary to show the environment in which the design is associated.
